SIDE RAIL FOR A TABLE

Herman W. Bernard, 304 Edgedale Drive,
High Point, N.C. 27403

Filed Oct. 29, 1968, Ser. No. 14,338

Term of patent 7 years

Int. Cl. D6—01

U.S. Cl. D33—14

FIG. 5

FIG. 2

FIG. 3

FIG. 1

FIG. 4

FIG. 1 is a front elevational view of a side rail for a table embodying my design;

FIG. 2 is an enlarged front elevational view of a right half-section of the rail of FIG. 1;

FIG. 3 is a top plan view of FIG. 2;

FIG. 4 is a left end elevational view of FIG. 2; and

FIG. 5 is a right elevational view of FIG. 2.

I claim:

The ornamental design for a side rail for a table, as shown.
